CLAIM

The ornamental design for a shoe, as shown and described.

DESCRIPTION

FIG. 1 is a bottom lateral perspective view of a shoe showing my new design;

FIG. 2 is a top plan view of the shoe, thereof;

FIG. 3 is a lateral side elevation view of the shoe, thereof;

FIG. 4 is a medial side elevation view of the shoe, thereof;

FIG. 5 is a rear elevation view of the shoe, thereof;

FIG. 6 is a front elevation view of the shoe, thereof; and,

FIG. 7 is a bottom plan view of the shoe, thereof.

In FIGS. 1-7, all broken lines on the upper of the shoe, including any laces and logo, form no part of the claimed design. Also, the broken lines on the outsole, including any logos, form no part of the claimed design.

1 Claim, 6 Drawing Sheets
